Application November 11, 1929
Serial No. 406,184

19 Claims. (Cl. 70—46)

This invention relates to lock construction and more particularly to lock construction for use on doors, and the like.

One of the objects of this invention is to provide a simple, rugged and thoroughly practical mechanism for fastening a door, or the like, in closed position, capable of rapid and inexpensive manufacture, and capable of reliable and efficient action. Another object is to provide a construction of the above-mentioned character in which the individual parts may be of simple construction and capable of rapid assembly. Another object is to provide a lock construction having a rotary bolt or bolts and to provide bolt-extending and 15 rotating mechanism that will be of simple and inexpensive construction and thoroughly dependable in action. Another object is to provide a rotary bolt lock construction in which forced reverse rotation of the extended bolt or bolts is made impossible and, moreover, by a mechanism that will be free from cumbersome or expensive complication. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which are shown several of various possible embodiments of this invention,

Figure 1 is a front elevation of the lock mechanism associated with a keeper, the parts being shown in the relation they have when applied to a door;

Figure 2 is a rear view with the back cover of the casing removed, thus showing the assembled mechanism;

Figure 3 is an end elevation as seen from the left of Figure 2;

Figure 4 is a rear view with the back cover removed showing the relation of the parts with the bolts extended and rotated into the keeper;

Figure 5 is a vertical sectional view, as seen along the line 5—5 of Figure 2;

Figure 6 is a vertical sectional view, as seen along the line 6—6 of Figure 2;

Figure 7 is a view similar to that of Figure 2, certain parts, however, being broken away in order to show certain other features of the construction more clearly;

Figure 8 is a vertical sectional view, as seen along the line 8—8 of Figure 2;

Figure 9 is a vertical sectional view, as seen along the line 9—9 of Figure 4;

Figure 10 is a rear view with the back cover removed of a possible modified form, the keeper being omitted for the sake of simplicity;

Figure 11 is a rear view showing certain features of the rear cover construction and indicating the relation of certain of the parts with the bolts in extended position;

Figure 12 is a sectional view along the line 12—12 of Figure 10;

Figure 13 is a vertical longitudinal sectional view, as seen along the line 13—13 of Figure 10;

Figure 14 is a perspective view on a smaller scale of one of the parts seen in plane in Figure 10, and

Figure 15 is a fragmentary sectional view, as seen along the line 15—15 of Figure 10.

Similar reference characters refer to similar parts throughout the several views in the drawings.

Referring now to the drawings and more particularly to Figures 1, 2 and 4, there is generally indicated at 20 a casing open at its rear and provided interiorly with suitable lugs 21 (Fig. 4) against which may rest a cover plate 22 (Fig. 6) and into which are threaded the cover-securing screws 23. The left-hand wall of the casing, as viewed in Figures 1, 2 and 4, is provided with two openings shaped substantially as shown at 24 and 25 in Figure 3; these openings will be seen to have arcuate or circular portions and lateral extensions therefrom, and they are adapted to receive the left-hand ends of bolts 26 and 27, respectively, the bolts being preferably substantially cylindrical and having at their left-hand ends lateral projections 26^a and 27^b, respectively (see also Fig. 9). The curved or rounded portions of the openings 24 and 25 are adapted to contact with and guide the cylindrical portions of the bolts 26 and 27 as the latter are extended and rotated, while the lateral extensions of the openings 24 and 25 are adapted to house the lateral lugs 26^a, 26^b and 27^a, 27^b of the bolts when the latter are in withdrawn position, as shown in Figures 2 and 3.

The right-hand portions of the bolts 26 and 27 (Fig. 2) are preferably of reduced diameter, as at 26^c and 27^c, these reduced portions 26^c and 27^c extending into suitable bores formed in the upstanding lugs 28 and 29, respectively, of a sliding plate 30 guided for movement in a horizontal direction, as viewed in Figure 2, in suitable ways 20^a and 20^b (Fig. 5) extending lengthwise along the interior of the casing.

The front wall 20^c of the casing 20, as viewed in Figure 1, (the bottom wall, as seen in Figure 2, or the left-hand wall, as seen in Figure 6) has formed therein two grooves, generally indicated at 31 and 32 (see also Fig. 7), the former substantially underneath the bolt 26 and the latter substantially underneath the bolt 27, as viewed in Figure 2. The groove 31 has a portion 31^a extending lengthwise of the casing and hence in 10 the same direction substantially as the direction in which the plate 30 slides and the bolts are to move. Groove 32 has a similar portion 32^a.

Toward its left-hand end the groove 31 has a portion 31^b extending at a substantial angle to 15 the portion 31^a, preferably merging gradually by appropriate curvature into the portion 31^a. Groove 32 has a similar portion 32^b.

Bolt 26 is provided with a pin 33 suitably secured thereto and shaped to extend into the 20 groove 31 (see Fig. 6). Bolt 27 has a pin 34 projecting therefrom and extending into the groove 32.

Pivotedly secured to the left-hand portion of 25 the sliding plate 30 (Fig. 2) are two links 35 and 36, the pivotal connection being effected as by the pins 37 and 38, respectively. The left-hand ends of the links are suitably apertured (see Fig. 6) to permit the passage therethrough of the pins 33 and 34, respectively, before the latter 30 extend into the slots 31 and 32, respectively; this relation of the parts is clearly shown in Figure 6.

Rotatably mounted in the front wall 20^c of the casing 20 (see Fig. 5) is a manually operable knob 39 terminating upon the interior of the casing in 35 a crank 40 (Figs. 1, 4 and 7). The crank arm has a crank pin 41 extending through a transverse slot 30^a (Figs. 1, 4 and 7) in the sliding plate 30 and into a transversely slideable member 42 (Figs. 2 and 4) carried by the sliding plate 30 and guided 40 for transverse sliding movement by means of suitably spaced flanges 43 and 44 (Figs. 2 and 4) conveniently integrally formed with the plate 30.

The transversely sliding member 42 is bent or shaped, as is indicated at 42^a in Figure 5, so as to 45 be engaged by a spring 45 (Figs. 2 and 4) coiled about a spring 46 carried by the sliding plate, its other end abutting against the lug 29. The spring 45 tends to urge the slide member 42 downwardly, as viewed in Figures 2, 4 and 5.

The slide member 42 is of such a length that, when in either of the extreme positions of the other parts, as shown in Figures 2 and 4, the member 42 projects laterally of the sliding plate 30, and may be seated either in the recess 46, as in 50 Figure 2, or in the recess 47, as in Figure 4, formed on the interior of the side wall of the casing 20, and forming an abutment 48 between recesses.

Considering now the operation of the mechanism, it may first be pointed out that the parts 55 occupy the position shown in Figure 2 when the bolts are withdrawn. The spring 45 holds the slide member 42 in the recess 46, and hence to the right of the abutment 48, the member 42 thus preventing any movement of the slide 30 or of the parts associated therewith, the bolts 26 and 27 being effectively tied, as it were, to the plate 30 by means of the links 35 and 36. These links thus prevent relative movement between the bolts and the plate 30.

Also, the crank 40 (see Fig. 1) is held so that the axis of the knob 39 and the axis of the crank 41 are in substantially the same line as the line of movement of the sliding plate 30, and the parts being thus on dead center, the crank 40 also acts to prevent movement of the slide 30.

Under these conditions, also, the left-hand ends of the bolts, together with the lateral projections thereon, are housed in the openings 24 and 25 of the left-hand end wall of the casing 20.

If now the knob 39 is rotated in counter-clockwise direction, as viewed in Figure 1, the crank pin 41 moves the slide member 42 upwardly, as viewed in Figure 2, and hence moves it out of the recess 46, continued movement of the crank arm 40 commencing a movement of translation, in a direction toward the left, of the slide plate 30, as viewed in Figure 2. This movement of translation is transmitted by the links 35 and 36 to the bolts 26 and 27 which thus are projected to the left and out of the end wall of the casing, the lug ends of which are thus made to pass through the opening 50 (Fig. 9) in the keeper 51, rotation of the bolts being prevented since the pins 33 and 34 (Fig. 6) thereof move along the portions 31^a and 32^a, respectively, of the grooves or slots 31-32, 95 respectively.

As the pins approach the left-hand ends of the portions 31^a and 32^a of the grooves 31 and 32, the curvature of the merging portions 31^b and 32^b of the grooves, under the force transmitted to the pins 33 and 34 through the links 35 and 36, respectively, the latter, during the initial movement, being at a substantial angle to each other, as is clear from Figures 1 and 2, cause the pins 33 and 34 to be swung about the axes of the bolts 26 and 27, respectively, and thus commence the rotation of the bolts themselves.

As the rotation of the bolts proceeds, the angle which the links 35 and 36 makes to the direction of movement of the sliding plate 30 continually increases, thus likewise increasing the rotational effect upon the bolts of the force or forces which continue the movement of the sliding plate 30 in a direction toward the left, as viewed in Figures 2 and 4.

Also, as this angle increases from the relatively small angle, as indicated in Figure 2, relative movement takes place between the bolts and the sliding plate, suitable sleeves 26^k and 27^k on the bolts 26 and 27 abutting against the interior face 120 of the left-hand end wall of the casing, as shown in Figure 4, thus preventing further movement of translation of the bolts themselves. The continued movement toward the left of the sliding plate 30, either under the control of the crank arm 125 40 or under the action of spring 45, bringing the parts into the position shown in Figure 4, the plate 30 having been slid in a direction toward the left, and the lugs 28 and 29 thereon having been moved toward the left along the reduced portions 130 26^a and 27^a of the bolts, these lugs coming to rest substantially against the shoulders formed by the larger-diamented portions of the bolts.

The links 35 and 36 are, by the time the movement of the sliding plate 30 has terminated, 135 brought into a position such that the line connecting their pivotal connections is substantially and preferably exactly at right angles to the line along which the plate 30 is movable. These links thus positively hold the bolts 26 and 27 140 against rotation, any force applied to the bolts to tend to unrotate them being transmitted through the links to the plate 30 in a direction at right angles to any possible movement of the plate 30, and thus no movement of the plate 30 145 can take place, and likewise no rotation of the bolts can take place.

At the same time the crank arm 40 has moved to another dead center position, as shown in Figure 4, and it acts to prevent movement to- 150

ward the right of the plate 30. Also, the transversely slideable member 42 has been moved into the recess 47 to the left of the abutment 48 and an additional lock against movement of the plate 5 30 toward the right has been achieved.

These locking actions upon the plate 30 are made to coat in a unique way with the bolts themselves to prevent forcing of the bolts inwardly from the exterior. It has already been 10 pointed out that the flanges 26^a and 27^a come to rest in a position abutting the inside face of the left-hand end wall of the casing 20 and that they thus prevent the bolts from being forceably pulled or forced further out of the casing. However, the lugs 28 and 29 (Figs. 2 and 4) having 15 been brought into abutting relation to the shoulders formed by the larger-diametered parts of the bolt, and these lugs 28 and 29 being carried by the locked plate 30, thus form solid abutments resisting any tendency to force the bolts inwardly from the exterior.

In unlocking the device, the crank arm 40 is given a rotation in a clockwise direction, as viewed in Figure 4, against the action of spring 25 45. Initial movement of the crank 40 moves the slide member 42 out of the recess 47 and continued movement thereof starts movement of the plate 30 in a direction toward the right, as viewed in Figure 4. This latter movement moves the pivot pins 37 and 38 of the links 35 and 36 30 toward the right, breaking the preferred 90° angle above-mentioned and, in effect, forcing the pins 33 and 34 to follow the portions 31^b and 32^b of the grooves 31 and 32, respectively, (Fig. 2) 35 thus unrotating the bolts. During the movement the lugs 28 and 29 slide along the portions 26^c and 27^c, respectively, of the bolts. By the time the pins 33 and 34 have completed a traverse of the substantially transverse portions of the grooves 31 and 32 respectively, the lugged head ends of the bolts have been brought into alignment with the greater dimension of the opening 50 in the keeper 51 so that the withdrawal of the bolts from the keeper may then proceed or 40 continue.

Continued rotation of the crank arm 40 in clockwise direction, as viewed in Figure 4, causes the plate 30 and the bolts 26 and 27 to move in a direction toward the right, as a unit, the pins 33 and 34 on the bolts moving along the portions 31^a and 32^a, respectively, of the slots or 45 grooves 31 and 32. The bolts are brought to a position of rest, substantially as shown in Figures 1, 2 and 7, in which the crank 40 has again assumed a dead center position and the transverse slideable member 42 positioned to the right of the abutment 48 and inserted in the recess 46 (Fig. 2). The spring 45 insures the completion 50 of movement of the parts into the position shown in Figure 2.

The cover plate 22 (Figs. 5 and 6) has rotatably mounted therein a crank 52 adapted to be rotated by a connecting bar 53 operatively related to the key cylinder 54 and operated under the control of a key 55. The crank 52 is provided with a crank pin 56 which, when rotated by the key, is adapted to engage the projecting portion 42^a of the transversely slideable member 42, thus moving the latter out of whichever recess 47 or 46 (Figs. 4 and 2) that the latter may be in, the crank pin 56 thereafter riding and sliding in between the portions 43^a and 44^a of the flanges 43 and 44 formed on the sliding plate 30, thus actuating the crank arm 40, the slide plate 30, and related parts, in a manner that

will now be clear in view of all of the foregoing.

Certain features of the manner of assembly of the above-described parts may now be briefly pointed out. Considering first the links 35 and 36, I prefer to have these links rest against the interior face 20^f of the front wall 20^e of the casing 20 (see Figs. 5, 6, 7 and 8), this face 20^f being spaced away from the guiding portions 20^a and 20^b by a distance substantially equal to the thickness of the links 35 and 36. The right-hand ends of the links, as viewed in Figure 2, thus extend underneath the left-hand portion of the plate 30. The pins 37 and 38 (Fig. 2) are either cast integrally with the plate 30 or are rigidly secured thereto, and extend freely into suitable openings in the right-hand ends of the links 35 and 36. The pins 33 and 34 (Figs. 6 and 8) on the bolts 26 and 27, respectively, simply extend through the openings in the left-hand ends of the links and into the grooves 31 and 32, respectively. The lugs 28 and 29 on the sliding plate 30 are of sufficient extent as to be substantially contacted by the cover plate 22 when the latter is put in place, as is seen in Figure 6, while at the right-hand end of the plate 30, the latter is provided with suitable upstanding portions 30^f and 30^g (Fig. 5) to just about engage the cover plate 22 when the latter is put in place.

The parts are assembled as above described, with respect to the links 35 and 36, the reduced diametered portions 26^c and 27^c of the bolts being passed into the lugs 28 and 29 on the sliding plate. The parts having been thus inserted into the casing, the crank pin 41, preferably in the form of a screw, is passed through the sliding member 42 and into the crank 40. The cover plate is then put in position, appropriately relating the key-operated crank 52 to the member 42 and the cover plate secured in position, as by the screws 23 (Fig. 6). The various mechanisms, while being freely slideable or movable relative to one another, are dependably held in assembled relation by the cover plate itself. To take the mechanism apart, it is simply necessary to remove the cover plate and the crank pin 41, whence the various parts are readily removed from the casing and removed from each other.

In Figures 10-15 I have illustrated a possible modification of my invention, adapted to achieve certain additional advantages. The bolts 26 and 27, provided with the projecting lugs at their head ends, as hereinabove described, are preferably of the same diameter throughout, and are guided in part by the rounded portions of the openings 24 and 25 in the left-hand end wall of the casing 20 and in part, also, by arcuate portions 20^k (Fig. 15) preferably cast with or otherwise formed upon the interior of the casing 20. These arcuate seats 20^k are of about 90° extent but, in a direction lengthwise of the bolts, they are cut away and curved, as is indicated at 20^l (Fig. 10), forming guiding side walls adjacent the inside face 20^f (Fig. 13) of the front wall 20^e of the casing 20 along which the left-hand end of the links 35 and 36, into which the pins 33 and 34 of the bolts project (Fig. 12), are guided.

The links 35 and 36 are preferably sheet metal stampings provided with end lugs 60 and 61 (Fig. 13) adapted to slide against the face 20^f and thus hold the body portions proper of the two links away from the face 20^f, interposing between the two sufficient space into which the bolt pins 33 and 34 may project.

The sliding plate 30 is preferably in the form of a sheet metal stamping and has punched and

bent downwardly (Figs. 14 and 13) two lugs 63 which extend into and through suitable recesses in the right-hand ends of the links 35 and 36, respectively. A spring 64 is coiled about a pin 65 (Fig. 10) and has two arms extending toward the left and into engagement with the bolt pins 33 and 34 (see Fig. 12), the spring acting to yieldingly urge the two spring arms, and hence the bolt pins, away from each other, as viewed in Figures 10 and 12, and thus causing the links to tend to separate or swing away from each other, as viewed in Figure 10, about the axes of the lugs 63 and 64. The spring 64 thus also insures that the left-hand ends of the links 35 and 36, and hence the bolt pins 33 and 34, follow the guiding portions 20^a (Fig. 10).

The sliding plate, as is better shown in Figure 14, is bent to provide longitudinally extending side flanges 66 and 67 of sufficient extent to be barely engaged by the cover plate 68 (Fig. 13) when the latter is put in place and secured in position as by the screws 69 which hold the plate against suitable lugs 70 (Fig. 10) cast into the inside of the casing 20.

The plate 30 has also cut and bent or stamped out of its main portion two transversely extending guiding flanges 71 and 72 and a transversely extending slot 73. Between the two flanges 71 and 72 there is slidably mounted and guided the transversely slidable member 42, shaped substantially as described in connection with Figures 1-9, and operated upon by a suitable spring 74 (Figs. 10 and 13). The crank 40, operated by the knob 39, extends into the casing 20 (see Fig. 13) and a crank pin in the form of a screw 75 passes through the slidable member 42 and into the crank 40.

Thus, as the crank 40 is swung in counterclockwise direction, as viewed in Figure 10, the slidable member 42 is lifted out of the recess 46 in the inside of the casing, the sliding plate 30 is moved to the left, the bolts 26 and 27 being extended out of the casing by the links 35 and 36 which, as above pointed out, connect the bolts to the sliding plate 30.

During this movement the spring 64 causes the left-hand ends of the links 35 and 36 to be moved along the straight portions of the guiding parts 20^a and as the movement continues, the spring 64 causes these portions of the links, and hence also the bolt pins 33 and 34, to follow the curved portions of the parts 20^a (Fig. 10), causing the links to swing away from each other and the bolts to rotate. The parts are so proportioned that the rotation of the bolts preferably does not commence until the bolts have been well extended into the keeper 51 (Fig. 9).

As this movement is completed, the crank 40, assumes a new dead center position, locking the plate 30 against movement in a direction toward the left or right, the slide member 42 is seated in the recess 47 and to the left of the abutment 48 on the inside of the casing, thus further locking the plate 30 against movement, while the links 35 and 36 will have assumed the positions shown in dotted lines in Figure 10, the lines connecting the pivot points of these links, extending preferably at right-angles to the line of movement of the sliding plate 30 itself.

To unlock the mechanism, the crank 40 is rotated in reverse direction, lifting the slide member 42 out of the recess 47 and also moving the crank 40 out of its dead center position; initial movement brings the links 35 and 36 out of alignment, thus unrotating the bolts, while continued

movement is accompanied by continued rotation and withdrawal of the bolts out of the keeper, final completion of the movement being accompanied by withdrawal of the bolts into the casing. The crank arm 40 moves to the dead center position shown in Figure 10 and the slide member 42 becomes seated in the recess 46, thus locking the parts in unlocked position.

A key-operated connecting bar 53, operable through a key cylinder 54 and key 55, as in Figure 5, extends into and connects with the crank 52 (Fig. 13) rotatably carried in the plate cover 68 and provided with a crank pin 56 adapted to coact with the portion 42^a of the slide member 42 and to slide in between and be guided by the flanges 71 and 72. Thus, the mechanism may be actuated under the control of the key, in a manner that will now be clear in view of all of the foregoing.

The cover plate 68 holds the various parts against disassembly, the flanges 66 and 67 (Fig. 14) of the plate 30 just engaging the underside of the cover plate 68, the plate 30 being guided by suitable portions 20^a and 20^b, similarly as in Figure 5.

The cover plate 68 has stamped and bent inwardly a suitable number of portions 68^a and 68^b, preferably two for each bolt (see Figs. 11 and 12) the inner ends of these portions having the same radius of curvature as the bolts themselves, and coacting with the portions 20^k (Fig. 15) to provide bearings and guides for the rotating and sliding bolts.

The assembly of the parts will be clear from the above but it might here be pointed out that the modified form immediately above described lends itself to rapid and inexpensive manufacture, many of the parts being capable of embodiment in the form of sheet metal stampings and thus having many advantages in the way of achieving economy of manufacture, all without sacrifice of dependability of operation.

It will thus be seen that there has been provided in this invention a lock construction in which the various objects hereinbefore set forth, together with many thoroughly practical advantages are successfully achieved. It will be seen that the construction is well adapted for manufacture on a large scale and well adapted to meet the varying conditions of hard practical use.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

I claim:

1. In a construction of the class described, in combination, a casing, a bolt extendable out of said casing and rotatable about an axis extending substantially in the direction of extending movement of said bolt, a pin projecting from said bolt, a member guided by said casing for movement in the direction of extension of said bolt and having a pin protecting therefrom, means for operating said sliding member, a link connecting said slide member with said bolt and having the pins thereof extending thereinto, and guiding means adapted to permit said link, upon substantial completion of the extension of said bolt, to assume a position such that the line connecting said pins extends substantially at right angles to the line of movement of said sliding member.

2. In a construction of the class described, in combination, a casing, a bolt extendable out of said casing and rotatable about an axis extending substantially in the direction of extending movement of said bolt, a pin projecting from said bolt, a member guided by said casing for movement in the direction of extension of said bolt and having a pin projecting therefrom, means for operating said sliding member, a link connecting said sliding member with said bolt and having the pins thereof extending thereinto, and guiding means in the form of a groove formed in said casing and having said bolt pin extending thereinto, said groove having a portion extending in the general direction of extending movement of said bolt and a portion extending at an angle thereto, said last-mentioned portion being of sufficient extent to permit said link, when said bolt is completely extended, to assume a position such that the line joining the two pins extends substantially at right angles to the line of extending movement of said bolt. 80
3. In a construction of the class described, in combination, a casing, a bolt extendable out of said casing and rotatable about an axis extending substantially in the direction of extending movement of said bolt, a pin projecting from said bolt, a link having pivotal connection at one end thereof with said pin, a rotary operating member, means forming a connection between said member and the other end of said link for transmitting bolt-extending movement to said bolt through said link, and means for causing a change in the angular relation between the link and the line of movement of said bolt to take place as said bolt is extended. 85
4. In a construction of the class described, in combination, a casing, a bolt extendable out of said casing and rotatable about an axis extending substantially in the direction of extending movement of said bolt, a pin projecting from said bolt, a link having pivotal connection at one end thereof with said pin, a rotary operating member, means forming a connection between said member and the other end of said link for transmitting bolt-extending movement to said bolt through said link, and means for causing said link to assume a position substantially in line with the direction of rotary movement of said pin when the bolt is in extended position. 90
5. In a construction of the class described, in combination, a casing, a bolt extendable out of said casing and rotatable about an axis extending substantially in the direction of extending movement of said bolt, a pin projecting from said bolt, a link having pivotal connection at one end thereof with said pin, a rotary operating member, means forming a connection between said member and the other end of said link for transmitting bolt-extending movement to said bolt through said link, and means for determining the rate and extent of rotary movement of said bolt as the latter is extended, said means being constructed to cause said link to assume a position extending substantially in line with the direction of rotary movement of said pin when the bolt is completely extended. 95
6. In a construction of the class described, in combination, a casing, a bolt extendable out of said casing and rotatable about an axis extending substantially in the direction of extending movement of said bolt, a pin projecting from said bolt, a link having pivotal connection at one end thereof with said pin, a rotary operating member, means forming a connection between said mem- 100
- ber and the other end of said link for transmitting bolt-extending movement to said bolt through said link, and guiding means for said pin, said guiding means having a portion extending in the general direction of extending movement of said bolt and another portion extending at an angle thereto, said last-mentioned portion being of a sufficient extent to permit such rotation of the bolt and such a swinging of said link that the longitudinal axis of the latter is substantially in line with the direction of rotary movement of said pin. 105
7. In a construction of the class described, in combination, a casing, a pair of bolts extendable out of said casing and rotatable about an axis substantially coincident with the direction of extending movement thereof, a pair of links each pivotally connected at one end thereof to one of said bolts, and means for giving a movement of translation to the other ends of said links, thereby to extend the bolts, and to cause said links to assume ultimate positions substantially at right angles to the direction of extending movement of said bolts when the latter are substantially entirely extended. 110
8. In a construction of the class described, in combination, a casing, a pair of bolts extendable out of said casing and rotatable about an axis substantially coincident with the direction of extending movement thereof, a pair of links each pivotally secured to one of said bolts, movable means joining the other ends of said links, and means acting in response to movement of said movable means for ultimately positioning said links in substantial alinement with each other. 115
9. In a construction of the class described, in combination, a casing, a bolt extendable out of said casing and rotatable about an axis substantially coincident with the direction of extending movement thereof, a sliding plate within said casing and having a connection with one end of said bolt adapted rotatably to support said end of said bolt while permitting relative movement therebetween in the direction of the axis of said bolt, a link pivotally connected at one end to said bolt and at the other end thereof to said sliding plate, and means permitting rotation of the bolt and relative movement between said bolt and said sliding plate to take place only after a predetermined movement of projection of said bolt has taken place. 120
10. In a construction of the class described, in combination, a casing, a bolt extendable out of said casing and rotatable about an axis substantially coincident with the direction of extending movement thereof, a sliding plate within said casing and having a connection with one end of said bolt adapted rotatably to support said end of said bolt while permitting relative movement therebetween in the direction of the axis of said bolt, a link pivotally connected at one end to said bolt and at the other end thereof to said sliding plate, and means permitting rotation of the bolt and relative movement between said bolt and said sliding plate to take place only after a predetermined movement of projection of said bolt has taken place, said means permitting said link to assume a position substantially at right angles to the line of movement of said bolt when the latter is substantially extended. 125
11. In a construction of the class described, in combination, a casing, a bolt extendable out of said casing and rotatable about an axis substantially coincident with the direction of extending movement thereof, a sliding plate within said cas- 130
12. In a construction of the class described, in combination, a casing, a bolt extendable out of said casing and rotatable about an axis substantially coincident with the direction of extending movement thereof, a sliding plate within said cas- 135
13. In a construction of the class described, in combination, a casing, a bolt extendable out of said casing and rotatable about an axis substantially coincident with the direction of extending movement thereof, a sliding plate within said cas- 140
14. In a construction of the class described, in combination, a casing, a bolt extendable out of said casing and rotatable about an axis substantially coincident with the direction of extending movement thereof, a sliding plate within said cas- 145

- ing and having a connection with one end of said bolt adapted rotatably to support said end of said bolt while permitting relative movement therebetween in the direction of the axis of said bolt, a 5 link pivotally connected at one end to said bolt and at the other end thereof to said sliding plate, and means permitting rotation of the bolt and relative movement between said bolt and said sliding plate to take place only after a predetermined 10 movement of projection of said bolt has taken place, said means including a projecting portion on the bolt and guiding means formed in said casing coacting therewith and permitting such a range of rotary movement of said bolt that 15 said link, when said bolt is substantially fully extended, assumes a position substantially at right angles to the direction of projecting movement of said bolt. 12. In a construction of the class described, in 20 combination, a casing, a bolt extendable out of said casing and rotatable about an axis extending substantially in the direction of extending movement of said bolt, said bolt having a shoulder intermediate its length, a movable member 25 within said casing and forming a bearing for rotatably and slidably supporting that portion of the bolt innermost of said shoulder, means causing said movable member and said bolt to move together and then to cause said movable member 30 to move lengthwise of said portion of said bolt, means responsive to said last-mentioned movement of said movable member to rotate said bolt, and means for locking said movable member in position. 35 13. In a construction of the class described, in combination, a casing, a bolt extendable out of said casing and rotatable about an axis extending substantially in the direction of extending movement of said bolt, a link pivotally connected to 40 said bolt to rotate said bolt, means adapted to cause said link to move to a dead center position when said bolt has been extended and rotated, and means for preventing movement of said link 45 out of dead center position and including a rotatable member movable into dead center position. 14. In a construction of the class described, in combination, a casing, a bolt extendable out of said casing and rotatable about an axis extending substantially in the direction of extending movement of said bolt, toggle means for effecting rotation of said bolt upon extension thereof and adapted to assume a dead center position, and means movable to dead center position for preventing 50 breaking of said toggle out of dead center position. 15. In a construction of the class described, in combination, a casing, a pair of bolts extendable out of said casing and rotatable about an axis substantially coincident with the direction of extending movement thereof, two pivotally connected links each pivotally connected to one of 55 said bolts for effecting rotation of said bolts when the latter are out of said casing and adapted to be moved into such a position that their longitudinal axes extend at right angles to the direction of extending movement of said bolts, thereby to prevent reverse rotation of the bolts, and means including a crank arm movable to dead center position for holding said links in straight-line relation. 16. In a construction of the class described, in combination, a casing, a pair of bolts extendable out of said casing and rotatable about an axis substantially coincident with the direction of extending movement thereof, a pivotally connected member for rotating each bolt and adapted to be moved to dead center position to prevent reverse rotation of its associated bolt, and means movable to dead center position for preventing movement of said members out of dead center position. 17. In a construction of the class described, in combination, a casing, a bolt extendable out of said casing and rotatable about an axis extending substantially in the direction of extending movement of said bolt, a pin projecting from said bolt and toward a wall of said casing, a movable member guided by the interior of said casing and having a pin projecting toward said wall of said casing, a link having two openings, each for the reception of one of said pins, said link being positioned adjacent said wall of said casing, and means including a cover plate for said casing for holding said parts in assembled relation. 18. In a construction of the class described, in combination, a casing, a bolt extendable out of said casing and rotatable about an axis extending substantially in the direction of extending movement of said bolt, said bolt having a shoulder intermediate its length, a movable member within said casing and forming a bearing for rotatably and slidably supporting that portion of the bolt innermost of said shoulder, means causing said movable member and said bolt to move together and then to cause said movable member to move lengthwise of said portion of said bolt into abutting relation to said shoulder, means functioning during a later portion of the movement of said movable member for rotating said bolt, and means for locking said movable member against retrograde movement and thereby to hold it in abutting relation to the shoulder on said bolt. 19. In a construction of the class described, in combination, a casing, a rotatable and extendable bolt therein, means adapted upon actuation to extend and rotate said bolt and constructed to assume a dead center position on the completion of its actuation, and rotary means for actuating said first-mentioned means and constructed to assume a dead center position for preventing movement of said first-mentioned means out of its dead center position.
